(57) **CLAIM**

The ornamental design for a terminal holder for reduced crosstalk connector, as shown and described.

DESCRIPTION

FIG. 1 is a front, top, and right side perspective view of a terminal holder for reduced crosstalk connector, showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof;

FIG. 7 is a right side elevational view thereof;

FIG. 8 is front, bottom and left side perspective view thereof; and,

FIG. 9 is a perspective view thereof, in use condition.

The broken line showing of environment in FIG. 9 is for illustrative purposes only and forms no part of the claimed design.
